UNITED STATES PATENT OFFICE.

MARIO CARINI, OF BELLE VERNON, PENNSYLVANIA, ASSIGNOR OF ONE-HALF TO
ARTHUR VANNUCCI, OF BELLE VERNON, PENNSYLVANIA.

SPRAYING MECHANISM FOR COKE OVENS.

Application filed April 23, 1924. Serial No. 708,480.

To all whom it may concern:

Be it known that I, MARIO CARINI, a citizen of the United States, residing at Belle Vernon, in the county of Fayette and 5 State of Pennsylvania, have invented certain new and useful Improvements in Spraying Mechanism for Coke Ovens, of which the following is a specification.

This invention relates to novel and improved spraying mechanism for coke ovens and is especially designed for use in connection with a single or a plurality of ovens, whereby water is delivered upon the coked material while still hot in the oven in order 10 that said material shall be cooled to a temperature at which it may be safely handled.

The prime object of the invention is to provide simple, durable, efficient and comparatively economical means for the purpose, said means constituting a labor saving device to such an extent, that one employee can perform the work of three, and at the same time accomplish the desired purpose more accurately and thoroughly than it has 15 been done heretofore.

A further object of the invention is to so construct my improved device that the sprinkling means may be automatically shifted into and away from the ovens, and 20 moved from one series of ovens to another series at the will of the operator.

Further and more specific objects of the invention are to provide a motor operated device which shall include means connected therewith adapted to impart a partial rotary 25 movement back and forth to all of the sprinkling pipes simultaneously; mechanism for shifting said means out of gear; means so constructed as to permit the use of the 30 device in connection with a single oven or simultaneously with a series of ovens; and means for reversing the movement of the device both longitudinally and transversely.

The foregoing and such other objects as 35 may occur from the ensuing description are accomplished by the combination, arrangement, construction and location of the several parts hereinafter more fully described, illustrated in the accompanying drawings 40 and particularly set forth in the claims appended hereto, it being understood that slight changes in the precise form, proportions and minor details of construction may be resorted to without departing from the

spirit or sacrificing any of the advantages 55 of the invention.

In the accompanying drawings forming a part of this specification it will be seen that:—

Figure 1 is a plan view illustrating the 60 improved device embodying my invention.

Figure 2 is a front elevation of the same.

Figure 3 is a side elevation.

Figure 4 is a cross-section taken in the 65 plane of the dotted lines 4—4, Fig. 2, looking in the direction of the arrows.

Figure 5, is an inside elevation taken in the plane of the dotted lines 5—5, Fig. 1, looking the direction of the arrows.

Figure 6 is an enlarged longitudinal section 70 showing a portion of one of the water distributing pipes broken away.

Figure 7 illustrates a bottom view of a portion of one of the water distributing 75 pipes broken away, and

Figure 8 is an enlarged cross-section of the pipe shown in Fig. 7.

In the embodiment of my invention as illustrated it will be seen that the improved spraying device is suitably mounted upon a truck which is adapted to be moved along on the track rails 1 which are usually installed along the front of and parallel with a series of coke ovens, said truck consisting of the usual wheels 2, axles 3, and longitudinal beams 4, and as clearly shown, this truck is provided with transversely arranged beams 5, upon the upper face of each of which is suitably mounted a rack 6, and transverse beams 7 upon the upper face of each of which is mounted a suitable track rail 8, for the purpose hereinafter described.

The movable spraying mechanism is formed with two upright metallic plates 9 and 10 constituting a part of the supporting frame, and formed integral with the lowermost end of the plate 9 is a lateral extension 10' upon which is suitably mounted an electric motor 11, provided with the usual drive shaft 12 and a driving gear wheel 13 fixedly mounted at the outer end of said shaft. Mounted in the upright frame 13' carried by the extension 10', is a shaft 14 to which is secured a larger gear wheel 15, meshing with said gear wheel 13, and a small gear wheel 16 meshing with a gear wheel 17 mounted on a stub-shaft 18 se-

cured to said frame 13', the latter gear 17, meshing with a gear wheel 18' secured to the shaft 19, said shaft 19 being mounted in the top portion of the upright frame 13', and to the outer end of said shaft 19 is fixedly mounted a gear wheel 20 adapted to mesh with the gear wheel 20' adjustably mounted on a stub shaft 21 within the slotted portion 22' of the upright plate 9, said gear 20' being adapted to mesh with the large gear wheel 22, the latter meshing with the teeth formed on the rack 6, a similar gear wheel 22' being mounted at the other end of the shaft 23 and meshing with the gear teeth on said rack 6. Said shaft 23 and gear wheels 22 and 22' are mounted on the upright frame portions 9 and 10 constituting a supporting medium for the water spraying means, said uprights being connected and braced by the intermediate bars, or beams 24, 24', and a beam 25 fixedly secured to the top portion of the uprights.

Secured to the upper face of the bar 25 is a series of bearings 26, each bearing embracing a water distributing pipe 27 to each of which is removably secured a spraying pipe 28, the inner end portion of each pipe 27 being revolvably secured within the outer end portion of a stationary pipe section 29, each of said pipe sections 29 having a flanged end portion 30 provided with securing bolts 31 and nuts 32 by which each section 29 is fixedly secured to the outer flanged end portion of a pipe 33, each of the pipes 33 being formed integral or connected with what may be termed a larger header pipe 34, to which is suitably connected a manifold water feed pipe 35 in communication with said header pipe 34. This header pipe is provided with a plurality of suitable cut-off valves 36, 37, 38 and 39, for the purpose hereinafter described.

It will be perceived that the water spraying pipes are arranged in a series of three distributing pipes for each oven, and as illustrated the device is shown as being adapted to cool the coke in three ovens simultaneously, although it will be understood a more or less number of ovens may be sprayed if desired, by simply lengthening the header pipe and the supply manifold pipe, and it will be seen that when all of the cut-off valves are closed and the valve 36 is opened one set of three spraying pipes at the right hand side of the device, are caused to spray water over the hot coke, then by opening valve 37, the middle set of three pipes are caused to spray the coke with water, and by opening the valves 38 and 39 all of the spraying pipes are caused to spray water into three ovens simultaneously, hence it is readily obvious that by the proper manipulation of said cut off valves any one set of three spraying pipes may be caused to operate separately, or all of them at the

same time, depending upon the will of the operator in charge.

It will be seen that a gear wheel 40 is secured to the outer side of the upright 9, by a stub shaft fixedly secured to said upright, and to a lateral extension 41 formed integral with the gear 40, or fixedly secured thereto, is connected one end of a link 42 and to the other end of said link is pivotally connected the outer end of an arm 43 which is fixedly connected with one of the pipes 27, and rigidly connected with the middle pipe 27, of each series of three pipes 27, is a yoke lever 44, each of said yoke levers having an upward extension 45, the upper end portion of which is pivotally connected with a bar 46, and a lower extension 47, to each of which is pivotally connected one end of a link 48, the other end of each link 48 being pivotally connected to the lower end portion of an arm 49 at the right hand side of each yoke lever 44, each of said arms being rigidly secured to one of the pipes 27, while near the upper end of the extension 45 of each yoke lever 44 is pivotally connected one end of a link 50, the other end of each link 50 being pivoted to an upwardly extending arm 51 disposed at the left hand side of the yoke lever 44, said arm 51 being rigidly connected to one of the pipes 27; hence it will be readily understood that when motion is imparted to the gear wheel 40 through the medium of the driving gear adapted to mesh therewith, the rotary movement of said gear wheel 40 will impart to each of the water spraying pipes about a quarter turn or revolution back and forth in opposite directions, through the medium of the links, yokes, arms and bar hereinbefore referred to, thus causing the water to be sprayed regular and continuous through the perforations 52 formed through the bottom portion of each spray pipe without spraying the side walls of the oven.

Mounted on the extension 10' at a right angle to the upright frame 13', is another upright frame 53, and at the upper end of said frame 53 is mounted a shaft 54 having fixedly secured at one end thereof, a friction disk 55, while at the other end of said shaft 54 is fixedly mounted a sprocket wheel 56 to which is connected a suitable endless sprocket chain 57, the other end of said chain being connected to a sprocket wheel 57' suitably keyed to the axle 3 of the truck within the groove or key-way 58 formed within the said axle, as clearly shown in Fig. 3. The shaft 19 is provided with another friction disk 59 which is adapted to be shifted by the friction clutch and lever 60 into contact with the disk 55, which through the medium of the driving means will impart a rotary movement to the sprocket wheel 56 and thus through the chain 57 to the sprocket wheel 57' whereby the truck and

its load is caused to be moved along the track to another set of ovens as desired. When it is desired to move the truck and its load in the opposite direction it is simply necessary to shift the friction disk 59 into contact with the opposite side of the face of the disk 55 by the shifting lever 60, as will be readily understood.

It will be seen by reference to Fig. 5 that a bell-crank lever 61 is pivotally secured to the outer end of the shaft 19, the short arm 62 of said lever being connected with the stub-shaft 21 which carries the gear 20', thus when the motor 11 is started by raising the lever 61 the gear 20' is caused to mesh with the gear wheel 22, thereby causing the spraying mechanism and its frame to be moved transversely over the rack until the said mechanism reaches the desired position with relation to the oven when by pressing downwardly on the lever 61, the gear wheel 20' is immediately shifted into engagement with the gear wheel 40, when a partial revolution back and forth is imparted to the spray pipes 28 by the means hereinbefore described, and the desired spraying operation is performed. When the spraying operation shall have been satisfactorily completed, it will be simply necessary to shift the driving gear 18', through the medium of the friction clutch and lever 63, into engagement with the gear wheel 15, and shift the gear 20' into contact with the gear 22 by an upward movement of the lever 61, when the driving gear will immediately cause the spraying mechanism to be returned to its initial position, and when it is desired to let the motor run idle it will be simply necessary to shift the driving gear wheel 18' into a position between the gears 15 and 17 by a proper manipulation of the lever 63.

By referring to Figs. 2 and 5 it will be seen that each upright 9 and 10 is provided near the bottom thereof with two small wheels 64, resting upon the tracks 8 and mounted on stub shafts 65' secured to said uprights, said wheels serving as an additional support and guide, in addition to the cog-wheels 22 and 22' engaging with the rack 6, for the spraying mechanism when it is caused to move into and out from the coke ovens.

The operation of the device may be briefly described as follows: When the motor has been started in the usual manner and it is desired to feed the spraying mechanism into the coke oven or ovens, and the gear wheel 20' has been shifted by the lever 61 into engagement with the cog wheel 22, the driving mechanism such as clearly shown in Fig. 2, will cause the spraying mechanism to be moved forwardly along the racks 6 and tracks 8, until it has reached the desired point with relation to the ovens, when

the lever 61 is immediately depressed thereby shifting the gear wheel 20' into engagement with the gear wheel 40 which will simultaneously cause a partial rotation of the spraying pipes back and forth, which operation will be continued until the coke shall have been sufficiently cooled, when by an upward movement of the lever 61, said gear wheel 20' will be shifted into engagement with the cog wheel 22, and simultaneously the gear wheel 18' is shifted by the lever 63 into engagement with the gear wheel 15 which action will cause the spraying mechanism and its supporting frame to be moved in a reverse direction and withdrawn from the ovens, when by the proper manipulation of the lever 60 the friction disks 55 and 59 are caused to engage with each other, thereby causing the truck and its load to be shifted along the track rails 1 by the drive sprockets 56 and 57' and the sprocket chain 57 into the desired position in front of another set of ovens for the purpose of repeating the spraying operation if desired.

It will be understood that a suitable hose is connected at one end to any well known source of water supply, while the other end is suitably connected at 65 with the feed water manifold 35.

Having thus described my invention what I claim and desire to secure by Letters Patent is:—

1. A device of the character described, comprising a truck having a plurality of cog-racks mounted transversely thereon, a plurality of metallic plate uprights provided with cog-gears engaging said racks, a beam connecting said uprights at their top portions, a series of spraying pipes resting on said beam, and means connected to one of said uprights and to each of the pipes for imparting a partial back and forth rotary movement to each of said pipes.

2. A device of the character described, comprising a truck having a plurality of cog-racks mounted transversely thereon, a plurality of metallic plate uprights having mounted thereon cog-gears engaging said racks, a longitudinal beam connecting the top portion of each upright plate, a series of water spraying pipes secured on said beam, and means connected with one of the upright plates and each of said pipes for imparting a back and forth rotary movement to the entire series of pipes.

3. A device of the character described, comprising a truck having a plurality of cog-racks mounted transversely thereon, a plurality of metallic uprights, a plurality of wheels and cog-gears secured to said uprights adapted to support said uprights in engagement with said cog-racks, a beam connecting the uprights at their top portion, a series of spraying pipes supported on said

- beams, and means connected to one of the uprights and to each pipe for imparting a back and forth rotary movement to each of the said pipes.
- 5 4. A device of the character described, comprising a truck, spraying mechanism movably mounted on said truck, consisting of a pair of metallic upright plates connected at their top portion by a longitudinal beam, one of said plates being formed with a lateral extension at its bottom portion, an electric motor mounted on said extension, means mounted on the extension and connected with the motor and engaging with mechanism mounted on one of the upright plates for imparting a forward and rearward movement to said spraying mechanism transversely of said truck.
- 10 5. A device of the character described, comprising a truck, spraying mechanism mounted on said truck, consisting of two upright metallic plates provided with cog-gears and wheels, one of said plates being formed with a lateral integral extension,
- 15 20 25 30 35 40 45 50 55 60 65 70 75 80 85 90 95 100 105
- 25 a beam connecting the top portion of each upright, a series of spraying pipes mounted on said beam, means mounted on said extension and one of the uprights for imparting a forward and rearward movement to said mechanism, and means connected to one of the uprights and to each of said pipes for imparting a back and forth rotary motion to each of said pipes.
6. Spraying mechanism for coke ovens mounted on a truck, comprising two metallic uprights, a beam connected to the top portion of each upright, a series of stationary pipes connected with a larger header pipe mounted on said beam, a series of water spraying pipes revolvably connected with said stationary pipes, and means connected with one of said uprights and each of the spraying pipes for imparting back and forth rotary motion to each of the spraying pipes.
7. Water spraying mechanism for coke ovens movably mounted on a truck, comprising two metallic uprights, a beam connecting the uprights at their top portions, a series of stationary pipes formed integral with a header pipe mounted on said beam, a spraying pipe revolvably secured to each stationary pipe, and means connected to one of the uprights and to each spraying pipe
- to simultaneously impart a rotary movement back and forth to each spraying pipe.
8. Water spraying mechanism for coke ovens movably mounted on a truck, comprising two metallic uprights, a beam connecting the top portion of said uprights, a series of stationary pipes connected to a header pipe mounted on said beam, movable means mounted at the bottom of each upright, a lateral extension forming a part of one of the uprights, means mounted on said extension and engaging with means mounted on one of the uprights for imparting a forward and rearward movement to said mechanism, a series of spraying pipes revolvably connected to the stationary pipes and means secured to one of the uprights and to each spraying pipe for imparting a partial rotary movement back and forth to each of said spraying pipes.
9. Water spraying mechanism for coke ovens movably mounted on a truck, comprising two uprights provided with moving means at their bottom portion adapted to travel transversely of said truck, a beam connecting said uprights at their top portions, a lateral extension forming a part of one of the uprights, means supported on said platform engaging means carried by one of the uprights for imparting a forward and rearward movement to said mechanism, a series of spraying pipes supported on said beam, and means connected with one of the uprights and to each spraying pipe for simultaneously imparting a rotary movement to each spraying pipe.
10. Water spraying mechanism of the character described mounted transversely on a truck, comprising two uprights with moving means secured thereto adapted to travel across said truck, a beam connecting said uprights, a series of spraying pipes mounted on said beam; a lateral extension forming a part of the bottom portion of one of the uprights, means carried by said extension and one of the uprights for imparting a forward and rearward movement to said mechanism, means mounted on said extension and connected with the truck axle for imparting movement to the truck, and means for simultaneously imparting a partial rotary movement to all of the spraying pipes at the same time.

MARIO CARINI.
